UNITED STATES PATENT OFFICE

LIONEL L. GINSBURG, OF SAGINAW, MICHIGAN, ASSIGNOR TO SAGINAW FURNITURE SHOPS, OF SAGINAW, MICHIGAN, A CORPORATION OF MICHIGAN

DESIGN FOR A CABINET

Application filed April 13, 1929. Serial No. 30,884. Term of patent 7 years.

To all whom it may concern:

Be it known that I, LIONEL L. GINSBURG, a citizen of the United States, residing at Saginaw, Saginaw County, Michigan, have invented a new, original, and ornamental Design for Cabinet, of which the following is a specification, reference being had to the accompanying drawing, forming part thereof.

The drawing is a perspective view of a cabinet, showing my new design.

I claim:

The ornamental design for a cabinet, as shown.

LIONEL L. GINSBURG.
